UNITED STATES PATENT OFFICE.

REUBEN H. RICKER, OF BOSTON, MASSACHUSETTS.

SWITCH FOR STREET-RAILWAYS.

SPECIFICATION forming part of Letters Patent No. 254,379, dated February 28, 1882.

Application filed December 23, 1881. (No model.)

To all whom it may concern:

Be it known that I, REUBEN H. RICKER, of Boston, in the county of Suffolk and State of Massachusetts, have invented a certain new and useful Improved Switch for Street-Railways, of which the following is a specification.

My invention relates to that class of street-railway switches that are provided with platforms, which, acting by the weight of the draft-
10 animals, operate the switch-point, its object being to so arrange moving weights to be operated by the platform that they (the said moving weights) shall, when the platform is tilted, hold it in its position against any tendency to rebound, or, in case the switch is located on a side incline, to so adjust the moving weights that they shall overcome the want of balance of the platform and still hold it in the desired position. I attain these objects by the
15 mechanism illustrated in the accompanying drawings, in which—

Figure 1 is a plan of my invention, the platform being represented as broken away to show the under or operating parts. Fig. 2 shows the parts in elevation and front section. Fig. 3 illustrates the working of the moving weights in cross-elevation, and Fig. 4 is the same in longitudinal elevation. Fig. 5 is an enlarged view, showing the working parts more in detail.
20 Fig. 6 is an enlarged view of the lower part of the weight-shifting device.

In the drawings, let A A' represent the main track of the railway to which my switch is to be applied, and B B' the siding of the same.

35 D and D', Figs. 1 and 2, represent the switch or frog plates, the plate D having a fixed point and the plate D' a swinging point. These two switch-pieces D and D' are made in every respect like the ordinary tongue-switch in use in street-railways.

The movable tongue E is connected to a diagonal rod, E², by means of a bolt, E'. This rod E² being operated by an arm, H, which projects downward from the platform-support H², the platform itself being represented by H², so that any oscillation of the platform H² will be transmitted through the support H', arm H, rod E², and bolt E' to the switch-tongue. (See Figs. 1 and 2.)

50 All of the above-described parts are in ordinary use, and are not of my invention.

The platform H² and its parts H' H is sup-

ported upon a fixed rod, K, upon which it oscillates, the rod K being stationary—that is, immovable about its axis.

55

L' is a trough or tube inclosing one or more moving weights, and is attached to a supporting-piece, L, said piece L being suspended upon a fixed pivot, M', which is held in position by means of vertical rods or plates M M, Fig. 4, 60 attached to the fixed rod K. This part L extends downward and terminates in a fork, N, so as to embrace the bolt h, which extends horizontally from the arm H of the platform-support H', so that the swinging motion of the 65 arm H will be communicated through this bolt h to the part L L', which causes the parts L L' to move, thus setting the weights in the tubes L' in motion.

h', Figs. 5 and 6, represents a sleeve loosely 70 fitting onto the bolt h, and serves to lessen the friction of the fork N.

The moving weights that I prefer are round balls W W' inclosed in the tube L'. (See Figs. 2 and 3.) These two weights W W' are free to 75 roll in the trough L' from either end to the center and then return. To prevent either of these weights from passing the center, I place a stop, L², as shown at Fig. 3. If desirable, the number of these rolling weights may be varied, and a track or groove may be provided for them to roll upon or in.
80

A modification of my device includes sliding weights, and in some cases both the rolling and sliding weights may be omitted, and 85 the ends of the part L' described as a trough may be made heavy, so that when the same is tipped out of position either to the right or left the tendency of gravity will be to hold them in such a position as to prevent the rebounding of the switch-point.
90

I do not wish to confine myself to the single-platform switch, as my invention will apply equally well to the switches in which two platforms—that is, one each side of one of the 95 rails—are used.

From the above it will be seen that a comparatively slight tilting of the platform H² will cause a much greater inclination of the weight-trough L'.
100

From the fact that the arm H swings about the center K while the part L swings about the center M', so that the angular movement of the part L is very much greater than the

angular movement of the part H, therefore the weights of the part L exert an overbalancing force to hold the switch in place.

I claim—

- 5 In a platform-switch, the combination of the moving weights W W' and the mechanism consisting of the trough L' L, pivot M', and arm H, whereby the said weights are made to

change their position whenever the platform is tilted, substantially as described, and for the purpose set forth.

REUBEN H. RICKER.
